UNITED STATES PATENT OFFICE.

ARCHIE O. STRICKLAND, OF WINFIELD, KANSAS.

FUEL-MAGAZINE.

1,298,819.

Specification of Letters Patent.

Patented Apr. 1, 1919.

Application filed May 16, 1918. Serial No. 234,999.

To all whom it may concern:

Be it known that I, ARCHIE O. STRICKLAND, a citizen of the United States, residing at Winfield, in the county of Cowley and 5 State of Kansas, have invented certain new and useful Improvements in Fuel - Magazines; and I do declare the following to be a full, clear, and exact description of the invention, such as will enable others skilled in 10 the art to which it appertains to make and use the same.

This invention relates to cooking ranges, and it relates more particularly to a fuel magazine for attachment to a stove or range.

15 One of the objects of this invention is to provide for the attainment of greater economy and convenience in the feeding of fuel to a stove or range of ordinary construction;

Another object is to provide a fuel drying 20 or seasoning means whereby green or wet wood may be prepared for burning after being placed in position to be burned when prepared, and in position to be automatically fed through a double pot-hole into the 25 ordinary fire box of the range;

Another object is to provide a fuel chamber or magazine of such size and shape with 30 relation to the size and shape of the lid-receiving depression around the double pot-hole in the top of the range that it may be seated in and extended beyond said depression so as to utilize a portion of the top of the range for holding the wood within the 35 magazine until it has become seasoned sufficiently to be burned;

Another object is to provide a device of this character which is strong, durable, and of such simple construction that it may be made at a minimum cost; and

40 Another object is to provide a magazine of this character which can be securely but removably attached to any cooking stove or range of ordinary construction;

Other objects and advantages may become 45 apparent to persons who read the following details of construction in connection with the accompanying drawings in which,—

Figure 1 is an end elevation of my improved fuel magazine attached to a stove, 50 only a portion of the latter being shown;

Fig. 2 is an enlarged vertical, central sectional view;

Fig. 3 is a top plan view, the parts being broken away and in section; and

Fig. 4 is a vertical sectional view along 55 the lines 4—4 of Figs. 2 and 3.

Referring to these drawings in detail, in which similar reference characters correspond with similar parts throughout the several views, the stove or range indicated at 5 60 is not described in detail, except to call attention to the opening or double pot-hole 6 which communicates with the fire box, and the depressed shoulder 7 which surrounds said opening at its margin. This double 65 pot-hole has straight sides and semicircular ends.

My improved fuel magazine comprises a chamber or hollow body 8 which is bottomless or has an open lower end. 70

The lower end is preferably wired at 9, so as to provide the greatest necessary rigidity, and this lower end is formed with depending elements 10 which are adapted to be seated on the straight portion of the depressed 75 shoulder 7 while the ends 11 rest upon the top of the range exteriorly of the depression 7. It will be seen, by reference to Fig. 3, that the length of the receptacle or chamber 8 is considerably greater than that of 80 the opening 6, so as to provide shelves at opposite ends of the chamber, and upon these shelves the piece or pieces of wood may rest within the chamber until they have become sufficiently seasoned to be burned. The 85 depending elements 10 are approximately as long as the straight part of the shoulder 7, and the curved or semicircular ends of the double pot-hole combine with the depending 90 elements 10 to prevent movement of the receptacle longitudinally of the double pot-hole.

In order that the wood may be placed within the chamber 8 without removing the latter from the stove or range, I provide 95 an opening which extends approximately from end to end of the chamber, and this opening is normally closed by means of a door or closure 12, hinged at 13, and provided with a handle 14 whereby it may be 100 swung upon its hinge or hinges. The upper end portions of chamber 8 are preferably semi-cylindrical and provided with reinforcing and supporting strips 15 which are also of semi-cylindrical form, and the semi-cylindrical closure 12 normally rests upon these supporting strips 15. Because of the entire 105 upper portion of my improved fuel maga-

zine being semi-cylindrical or convexed, it has the maximum strength consistent with lightness, and is less likely to become distorted by the heat than if it were shaped 5 otherwise.

For the purpose of removably securing this fuel magazine to the top of the stove or range, I provide a depending hook or L-shaped locking member 16 and a depending 10 hook or locking member 17. The securing or locking member 16 may be permanently fixed to the chamber 8 by any appropriate means, while member 17 may be either movably secured to the chamber 8 or be formed 15 of springy material, so that it may be flexed into and out of engagement with the stove or range. For the purpose of moving or flexing the element 17, I provide a push button or manipulative element 18 whereby the 20 spring securing or locking element 17 may be moved inward, and when thus moved, the magazine is unlocked and may be tilted forward so as to disengage the rear part thereof from the stove or range and then the magazine may be moved slightly rearward so as 25 to disengage the front portion.

From the foregoing, it is believed that the manner of applying and removing this magazine is obvious, and it will be seen that a 30 piece of wood or fuel which is too large or long to be placed directly within the fire box of the range may be first placed within the magazine and supported on the shelves at the ends of the latter. When a piece of 35 fuel is thus supported in the magazine, assuming that there is a fire in the fire box, this relatively large piece of fuel first becomes thoroughly seasoned and somewhat reduced by shrinkage, and then begins to 40 burn and thus becomes further reduced in size, and finally, its size is sufficiently reduced to allow it to pass by gravity into the fire box.

It will thus be seen that a great saving of 45 labor is accomplished by eliminating the necessity for cutting or splitting pieces of wood that are sufficiently small to enter the

magazine, but which are too large to enter the fire box of the stove or range; also, that a great saving of fuel is effected, because of 50 the fact that it is almost impossible to split certain gnarled and knotty pieces of wood, and these would be wasted and in the way if provision were not made for burning them without further reduction by mechanical 55 means.

It is not my intention to limit my invention to the exact details of construction as described in the foregoing, but I contemplate making minor changes within the 60 scope of the inventive idea disclosed in the foregoing description and appended claim.

What I claim as my invention is:

In an attachment for a stove which has in its top a double pot-hole having straight 65 sides and semicircular ends, said top having a depressed lid supporting shoulder surrounding said double pot-hole; a fuel chamber having an open lower end of greater length than said pot-hole whereby the extremities of said lower end rest upon the stove top, said lower end being also provided with straight depending elements adapted to drop into and be supported by said depressed shoulder, said straight depending 70 elements of said fuel chamber being of a length approximately equal to the length of the straight sides of the double pot-hole, whereby the ends of said straight depending elements coact with the semicircular ends of the double pot-hole to prevent shifting of the receptacle longitudinally of the double pot-hole, and means carried by the lower part of the fuel chamber and adapted to extend through the pot-hole and engage 75 with the under side of the stove top, to prevent tilting of the chamber.

In testimony whereof I have hereunto set my hand in the presence of two subscribing witnesses.

ARCHIE O. STRICKLAND.
